PEST DESTROYING EMULSION

Richard Neu, Dessau-Röslau, Anhalt, Germany,
assignor to Deutsche Hydrierwerke Aktien-
gesellschaft, Berlin-Charlottenburg, Germany,
a corporation of Germany

No Drawing. Application June 26, 1936, Serial
No. 87,465. In Germany June 26, 1935

1 Claim. (Cl. 167—24)

As it is known, the rotenone has the property of dissolving in aliphatic hydrocarbons but only to a little degree, so that solutions made in this way are unfit for the combating of vermin. In 5 aromatic hydrocarbons, it is true, the rotenone is easily soluble, but the thus obtained solutions are of a most toxic effect to the organism of mammals.

We also know the method of dissolving the 10 efficient ingredients of the derris-root and of the pyrethrum in acetone. Those solutions, however, cannot be worked with aliphatic hydrocarbons into the usual spraying means, as they don't last for a long time and the efficient ingredients, e. g. 15 those of the derris-root begin soon to precipitate. On the other hand, the solubility of the rotenone in aliphatic ketones is not sufficient to allow the manufacture of lasting preparations good for the purpose.

20 Now it has been found that it is quite easy to produce clear and lasting solutions of the rotenone, its derivatives and particularly of di-hydro-rotenone, pyrethrines, pyrethrum and derris-root-extracts in petroleum-distillates (kerosene), if 25 for the dissolving of the rotenone, etc., one makes use of cyclic ketones such as cyclo-pantanone, cyclo-hexanone or methyl-cyclo-hexanone, β -dekalinone and the like, to which partly or entirely hydrogenized cyclic hydrocarbons may be 30 added. The hydrogenation-products of the naphthalene, e. g. the tetrahydro- and the deka-hydro-naphthalene, have proved particularly apt for the purpose.

Furthermore it has been found that the 35 solutions of the rotenone, of its derivatives, of derris-root-extracts, of the pyrethrins or of the pyrethrum-extracts in cyclic ketones and hydrogenized aromatic hydrocarbons, are likewise fit for the use in an aqueous solution, if a neutral 40 emulsifying agent of high efficiency is admixed. Emulsifying agents of a particular fitness are the sulfonating-products of the fatty alcohols and especially those with 8 to 10 C-atoms, highly sulfonated Turkey-red oils and the like. These 45 solutions, when diluted with water, form good stable emulsions from which the efficient ingredients, which are colloidally distributed, precipitate very slowly in comparison with those containing merely a water-soluble solvent and a 50 wetting-out agent.

The hydrogenized aromatic hydrocarbons dis-

tinguish themselves—also compared with the usual solvents such as chloroform and benzene—by a lesser poisonous action and they don't possess any of the properties damaging the plants.

Example 1

In dissolving 0.5 g. of a 100%-rotenone (163° F) in 10 cm.³ of cyclohexanone (bearing 85% of ketone) and in adding 90 cm.³ of kerosene or a mixture of 10 cm.³ of tetra-hydro- and 10 of 10 deka-hydro-naphthalene, the rotenone will crystallize out after some time; but by the addition of a solution of 0.5 g. of rotenone in 10 cm.³ of cyclohexanone (85%), 10 cm.³ of tetrahydro-naphthalene, 20 cm.³ of dekahydronaphthalene 15 and 60-80 cm.³ of kerosene, one obtains a liquid which also after a long standing remains clear and which is very suitable for the combating of flies and gnats.

Example 2

In dissolving 0.5 g. of rotenone in 10 cm.³ of cyclohexanone (85%) and 10 cm.³ of deka-hydro-naphthalene and in adding 30 g. of an aqueous 30%-solution of the sodium salts of the sulfuric acid esters of fatty alcohols with 8-10 C-atoms, 25 one obtains a lasting, clear and transparent solution which, when diluted with water, is particularly fit for the combating of gadfly-grubs with pasture-animals. The dilution made with water and wherein the rotenone is fine-suspended, has 30 a milky-turbid aspect and it scarcely precipitates. This diluted solution is also an excellent means to combat the horticulture-damaging pests and doesn't do any harm to the plants.

Di-hydro-rotenone, derris-extracts, pyrethrins 35 and pyrethrum-extracts allow, in observing the above prescriptions, of being dissolved in quite the same way.

I claim:

A pest destroying aqueous emulsion consisting 40 of a poison of the group consisting of rotenone, di-hydro-rotenone, pyrethrines, pyrethrum- and derris-root extracts; cyclo-hexanone; hydrogenated naphthalene; with kerosene as a solvent; a fatty alcohol sulfonate having eight to ten carbon atoms in the molecule as an emulsifying agent and water, the cyclo-hexanone and hydrogenated naphthalene being present in substantial proportions and sufficient to produce a clear and lasting solution.

RICHARD NEU.
